ELECTRONIC FACIAL MUSCLE STIMULATOR

John I. Moss, Skokie, Ill., assignor to Relaxacizor, Inc.,
Los Angeles, Calif., a corporation of California

Filed Sept. 16, 1966, Ser. No. 3,887

Term of patent 14 years

(Cl. D83—1)

FIGURE 1 is a perspective view of an electronic facial muscle stimulator showing my new design;

FIGURE 2 is a side elevation view thereof;

FIGURE 3 is a top plan view thereof; and

FIGURE 4 is a bottom plan view thereof.

I claim:

The ornamental design for an electronic facial muscle stimulator, as shown.
